UNITED STATES PATENT OFFICE.

EDWARD J. WORCESTER, OF WORCESTER, MASSACHUSETTS.

IMPROVEMENT IN BUSH-HAMMERS.

Specification forming part of Letters Patent No. **138,975**, dated May 13, 1873; application filed March 1, 1873.

To all whom it may concern:

Be it known that I, EDW. J. WORCESTER, of Worcester, in the county of Worcester and State of Massachusetts, have invented a new and valuable Improvement in Bush-Hammers, and I do hereby declare that the following is a full, clear, and exact description of the construction and operation of the same, reference being had to the annexed drawing making a part of this specification, and to the letters and figures of reference marked thereon.

Figure 1 of the drawing is a representation of the bar of iron as pressed. Fig. 2 is a perspective view of my bush-hammer. Fig. 3 is a sectional view of the same.

My invention relates to certain improvements in the manufacture of bush-hammers used in stone-dressing; and it consists in a bar from which are cut the two sections composing the bit-holders, said bar being formed by rolling and planing instead of forging by trip-hammer or drop-hammer, as heretofore.

In the drawing, A represents a bar of iron which has been prepared and finished according to my improved process, ready to be cut into sections. The bars are first passed between the proper rollers a suitable number of times to upset the metal sufficiently and give the bars something of the required form. They are then placed in the planer and fin-

ished and dressed to the exact shape and dimensions required—that is to say, one surface of the bar has each side rounded as shown at *a*, and on the opposite surface is formed a central longitudinal groove, *b*, with a square shoulder, *c*, on each side. When the bars are finished and dressed they are cut by a milling-machine into pieces of the required width to form the sections B of the hammer. When the sections are placed together, as shown in Figs. 2 and 3, the grooves *b* form the eye for the handle, and the space between the shoulders *c* forms the recess for the bits D, which are placed in position with the gibs G at their bases, and the parts secured by screw-bolts E in the usual manner.

What I claim as new, and desire to secure by Letters Patent, is—

In the manufacture of bush-hammers, a bar formed by rolling and planing, from which the hammer sections may be cut, substantially as shown and described.

In testimony that I claim the above I have hereunto subscribed my name in the presence of two witnesses.

EDWARD J. WORCESTER.
